AARON KAMEN AND HERMAN KAMEN, OF BROOKLYN, NEW YORK

SLEEVE

Application filed July 11, 1931. Serial No. 550,054.

This invention relates to wearing apparel, and more particularly to a sleeve with an attached cuff, so constituted that the cuff is reversible to present two distinct faces to view.

One of the objects of this invention is to provide a sleeve with a reversible cuff wherein the cuff when reversed will be of the same width in either of its operative positions, and 10 wherein the cuff in folding from one position to the other, or vice versa, will bring about a lengthening or shortening of the sleeve to which it is attached. Thus, for ordinary wear the sleeve may be worn with the cuff in a position to lengthen the sleeve but when the wearer has work to do, which might soil the cuff, said cuff may be reversed to produce a shorter sleeve length and to present a different surface to the wear or vision, so that after 15 the work is done, that portion of the cuff which may have become soiled therefrom can be concealed by again reversing the cuff into its normal position.

The majority of reversible cuffs hereinbefore suggested are of the "French cuff" type. The present invention is not of this type, but is of the so-called single type, is permanently attached to the sleeve of the shirt and is incorporated into the sleeve construction in a 20 simple, novel and efficient manner as will hereinafter be more fully explained.

An important feature of the present invention resides in the fact that the structure is so constituted as to practically double the life 25 or wearing properties of the cuff, so that the cuff will in practice outwear the shirt with which it is associated.

Features of the invention, other than those specified, will be apparent from the herein- 30 after detailed description and claims, when read in conjunction with the accompanying drawing.

The accompanying drawing illustrates different practical embodiments of the invention, but the constructions therein shown are to be understood as illustrative, only, and not as defining the limits of the invention.

Figure 1 is a fragmental perspective section showing the structure embodying the 50 present invention. In this view the cuff is

turned up and is shown in section adjacent the buttonholes, so as to more clearly show the cuff construction.

Figure 2 is a similar view showing the cuff turned down or reversed. 55

Figure 3 is a section perspective through the cuff and sleeve showing the cuff in full lines in one position and in dotted lines in reversed position.

Figure 4 is a face view of the sleeve and 60 cuff with the cuff in turned up position.

Figure 5 shows the same structure with the cuff turned down.

Figures 6 and 7 show cuffs of different shapes. In Figure 6, the cuff is shown as 65 turned up and in Figure 7, the cuff is shown as turned down.

In the accompanying drawing, 1 designates a sleeve of the shirt to the lower end of which the cuff is attached. The manner 70 of forming the cuff is best shown in Figs. 1, 2 and 3. Here the cuff is illustrated as comprising three plies of material 2, 3 and 4, although the ply 3 may be omitted if de-

sired or one or more additional plies may 75 be introduced between the plies 3 and 4. In any event, the upper and lower edges of the several plies are turned in to form finished edges which are stitched down by rows of stitches 5 and 6. The ply 4 is formed in two 80 sections 4a and 4b. One of the sections 4a is sewed into the line of stitching 5, while one edge of the section 4b is sewed into the line of stitching 6. The other edges of the sections 4a and 4b are secured to shirt sleeves 85

1 by a line of stitching 7 and the cuff is thus attached to the shirt sleeve. The aggregate width of the sections 4a and 4b is somewhat greater than the width of the cuff and the section 4a is stitched along its medial line to 90 the section 4b by a line of stitching 8, all as clearly shown in Fig. 3. The purpose of the line of stitching 8 is to produce a well-defined fold line for the cuff for it is along this line that the cuff is folded from one position into reverse position or vice versa.

The manner of folding the cuff will be apparent from Figure 3. For example, when the cuff is in the full line position of this 95 figure, the section 4b of the ply 4 which is

the same width as the ply 2 will constitute the outer or exposed surface of the cuff, whereas if the cuff is folded along the line of stitching 8 into the dotted line position, 5 the ply 2 will then become the exposed surface of the cuff. It is highly important to this invention that the ply 4b be as wide as the ply 2 because if it were made narrower, the cuff when in one position would be narrower than in its other position.

With the construction as shown, however, the cuff is of the same width for both positions and the line of stitching 8 which constitutes the fold line is, in practice, so fine 15 and so relatively close to the top of the cuff that its presence is not apparent. The opposite ends of the cuff may be finished off in any suitable or appropriate manner. The cuff may be provided with squared ends, 20 curved ends or of any other desired ornamental shape, but the shaping of the cuff ends will make quite a difference in the operation of the cuff and in a manner in which the cuff or sleeve is constructed.

25 In Figures 4 and 5, the cuff is shown as provided with projecting tab ends, the tabs being sufficiently long so that the buttonholes 9 and 10 will come beyond the lateral edges of the sleeve opening. Thus, when the 30 cuff is turned up as shown in Fig. 4, an ordinary cuff button or link may be passed through these buttonholes beyond the edges of the sleeve, so as not to cause a wrinkling of the sleeve. When the cuff is turned down 35 as shown in Fig. 5, the button or link will not interfere with the sleeve irrespective of the shaping of the cuff. It is only when the cuff turned up that provision should be made to have the button or link clear the edge of 40 the sleeve. Any suitable button or link may be employed. That is to say, a straight or curved stiff shank sleeve button or a link may be employed or, if desired, two ordinary buttons may be backed up back to back on 45 opposite sides of the cuff and sewed through the cuff to one another. Irrespective of the type of button used, the cuff may be used as a round cuff or as the ordinary pear-shaped cuff.

50 In Figure 6, the cuff is shown as provided with a tab at only one end. Such a cuff is adapted to be worn as a round cuff only.

In Figure 7, the cuff is shown as having square ends without extensions and when 55 this is done, the sleeve should be cut away as shown at 11, so that the buttons or links will clear the edge of the sleeve opening when the cuff is turned up. The cuff shown in Fig. 7 may be used either as a round cuff or as a pear shaped cuff.

The cut out, similar to the cut out 11 in Fig. 7 may be also provided in the right hand edge of the sleeve opening of Fig. 6, 65 and when thus provided this structure may

be worn as either a round or a pear shaped cuff as may be desired.

The invention which has been described embodies many novel features which are important. For example, it will be noted that 70 cuffs made as described require only two buttonholes, whereas in many of the reversible cuffs heretofore suggested, four buttonholes are essential.

To manufacture buttonholes is expensive 75 and the insertion of cuff links or buttons through several buttonholes is a nuisance which many wearers will not tolerate. Furthermore, the cuff of this invention produces a relatively short sleeve length convenient 80 for working when in one position and a longer or dressy length when in the other position, but in both positions, the cuff is of the same width. This is an important practical feature of this invention. The cuff 85 as hereinbefore stated may be made of any desired number of plies and because of its peculiar formation and the manner of its folding, it may be either worn starched or soft. Furthermore, one face of the cuff may 90 be worn starched and the other soft.

It will be noted from the drawing and particularly from Fig. 3, that the portions of the ply sections 4a and 4b between the lines of stitches 7 and 8 constitute in effect a flange 95 extending from the cuff proper intermediate the edges of the latter. In other words, the cuff is provided intermediate its upper and lower edges with a flange of a length substantially equal to the distance which the base 100 of this flange is spaced from one edge of the cuff. That is to say, the distance between the lines of stitching 7 and 8 is substantially the same as the distance between the lines of stitching 5 and 8. It is as a result of this 105 arrangement that both faces of the cuff which are exposed to view are of the same width.

The drawing shows the invention in its preferred, practical forms, but the invention is to be understood as fully commensurate 110 with the appended claims.

In the drawing where extensions are shown at the end of the cuff, the extension is substantially triangular. If desired, however, more than one extension at each end of the 115 cuff may be employed, in which case, it may be desired to provide a buttonhole in each extension. This, however, is optional and will not generally be preferred.

Having thus fully described the invention, 120 what we claim as new and desire to secure by Letters Patent is:

1. In combination with a sleeve, a reversible cuff comprising one face ply stitched at its upper edge to the sleeve; a backing strip 125 also stitched at its upper edge to the sleeve; a fine row of stitching connecting the intermediate portion of the backing strip to the face ply above the middle of the face ply, and constituting a hinge about which the 130

cuff is reversed; an opposite face ply of the same width as the first face ply and stitched at one edge to the lower edge of the first face ply and at its opposite edge to the free edge 5 of said backing strip, whereby the backing strip provides a narrow backing therefor; said opposite face ply when the cuff is reversed presenting a plain, unbroken surface; and means whereby the cuff may be fastened 10 substantially midway between its edges in either reversed position, the overall length of the sleeve being changed by reversing the cuff without varying the cuff width.

2. In combination with a sleeve, a reversible cuff comprising one face ply stitched at its upper edge to the sleeve; a backing strip also stitched at its upper edge to the sleeve; a fine row of stitching connecting the intermediate portion of the backing strip to the 20 face ply above the middle of the face ply, and constituting a hinge above which the cuff is reversed; an opposite face ply of the same width as the first face ply and stitched at one edge to the lower edge of the first face ply 25 and at its opposite edge to the free edge of said backing strip, whereby the backing strip provides a narrow backing therefor; said opposite face when the cuff is reversed presenting a plain, unbroken surface; an extension 30 on one end of the cuff having fastening means beyond one edge of the placket opening; and complementary fastening means on the other end of the cuff.

In testimony whereof we have signed the 35 foregoing specification.
